REFRIGERATOR CONSTRUCTION

Leonard H. Darbyshire, Detroit, Mich., assignor
to Borg-Warner Corporation, Chicago, Ill., a
corporation of Illinois

Application July 20, 1938, Serial No. 220,239

2 Claims. (Cl. 220—15)

This invention relates to cabinet construction and more particularly to insulated cabinets of the type used for domestic refrigerators. This invention has particular reference to means for attaching an inner lining to an outer wall member for forming an insulated wall or door of the cabinet.

It is an object of this invention to provide a novel and cheaper form of cabinet construction.

It is another object of this invention to provide a refrigerator casing which is self-supporting having no internal frame for supporting either the casing or lining.

It is another object of this invention to provide a refrigerator cabinet which will be made up of as few parts as possible thus eliminating several steps in the assembly of the cabinet.

It is another object of this invention to provide a refrigerator casing which may be shaped from a single metal plate if desired.

It is another object of this invention to provide a refrigerator lining unit which may be attached directly to the refrigerator casing without any separate frame support and which may be installed through the front of the cabinet without any connections to be made from the rear of the refrigerator.

It is another object of this invention to provide a novel means for attaching a refrigerator lining to the casing in which the throat lining of the cabinet acts as a thermal break between the lining and casing.

It is another object of this invention to provide a door for closing a refrigerator cabinet comprising two metal plates which may be supported from each other without a separate frame member.

It is another object of this invention to provide a refrigerator cabinet which will have an increased capacity for any given size of cabinet.

It is another object of this invention to provide a refrigerator door in which a portion of the means holding the inner and outer panels of the door act as a thermal break between the two panels.

Other objects and advantages of this invention will be apparent from a consideration of the following specification and the attached drawings of which there are three sheets and in which:

Fig. 1 represents a front elevation of a refrigerator involving my invention;

Fig. 2 represents a side elevation of the cabinet shown in Fig. 1;

Fig. 3 represents a top plan view, partially

broken away, of the cabinet shown in Figs. 1 and 2;

Fig. 4 represents a section taken along the line 4—4 of Fig. 1;

Fig. 5 represents an enlarged view of the corner of the cabinet illustrated in Fig. 1 partially broken away to more clearly indicate the relation of the parts;

Fig. 6 represents a section taken along the line 6—6 of Fig. 5;

Fig. 7 represents an enlarged view of the corner of the door viewed from the back side of the door; and

Fig. 8 represents a top plan view of the refrigerator door partially broken away to indicate the relation of the parts.

In all views of the attached drawings the same numbers have been used to indicate the same parts shown. As shown in Figs. 1 and 2, the refrigerator consists generally of a casing 20 defining a door opening 22 and enclosing a machine compartment 24 and provision compartment 25. The casing 20 carries a provision compartment door 26 through which access is had to the provision compartment 25 defined by the lining 28. The cabinet may be supported upon a base 30 of any desired construction and has mounted in the machine compartment the machine supports 32 to which suitable condensing machinery may be fastened.

I have shown the refrigerator casing to be made up of two side panels 34, a top panel 36 and a back panel 38. These panels may be fastened together in any suitable manner such as by welding.

The casing also has a partition panel 40 which separates the machine compartment from the provision compartment. If so desired all of the panels may be shaped from one integral sheet of metal. The top panel 36 and the side panels 34 are bent to form flanges extending over a portion of the front and back of the cabinet as indicated at 42. The outside of the cabinet will be given some suitable finish such as porcelain or enamel.

The front portion of the machine compartment 24 may be covered with a suitable door 44 or that portion of the casing may be formed integrally with the side panels and may be shaped to simulate the appearance of a door. The front flange 42 of the casing panels has an inturned flange 46 formed along all four sides of the door opening. This flange is adapted to cooperate with a flange carried on the tank lining 28 which will be described later.

In this particular embodiment of my inven-

tion I have provided an opening 29 in the back wall 38 of the cabinet. This opening is to provide for the insertion of an evaporator into the tank lining from the rear of the refrigerator.

The tank lining 28 is a metal stamping which may be made of one piece or several pieces of metal welded together. The lining has a roll 58, formed around its open side, which acts to stiffen the lining and also to present a neat opening into the provision compartment. As shown in Fig. 4, the roll 58 has an outturned flange 52 formed on the forward side thereof. This flange 52 is arranged to be in alignment with the flange 46 on the casing when the lining is installed within the casing. Before the lining is inserted into the casing, suitable insulating material 54 will be installed around the inside of the casing. The tank will of course have an opening 29 in its rear wall to cooperate with the opening 39 in the casing.

For the purpose of holding the tank lining 28 rigidly to the casing 20, I have provided four turnbuckles 56 for engaging lugs 58 at each corner of the door opening of the casing and lugs 60 at each corner of the tank lining 28. The lugs 58 and 60 are formed of metal strips 62 which are bent double to form the lug and then bent at right angles to fit over the flanges 46 and 52. These metal strips 62 may be fastened to the flanges by spot welding. Each of the lugs 58 and 60 has a hole 64 punched in it which is adapted to receive a hooked end 66 of the turnbuckles 56. After the turnbuckles 56 have been engaged in the holes 64, it is obvious that the position of the tank 28, relative to the casing 20, may be adjusted by tightening or loosening the turnbuckles 56. If desired, the lugs 58 and 60 may be formed from part of the casing or tank as by offsetting a portion of the flanges 46 and 52 or the holes 64 may be punched directly in the flanges.

In order to fill the space between the flanges 52 and 46 and also to give the turnbuckles 56 something to pull against, I have provided separating strips 68 along each side of the door opening. As shown in Fig. 4, these separating strips have notches 70 and 72 cut along their edges adapted to receive the flanges 46 and 52, respectively. Each separating strip 68 may be shaped to hold a rubber gasket 74 between itself and the front edge of the tank roll 58. This gasket 74 assures a tight seal between the separating strip and the tank lining. Separating strips 68 will preferably be made of some heat insulating material such as wood or Bakelite and will be given a waterproof finish of pleasing appearance.

It will be noted from an inspection of Fig. 5 that the separating strips 68 extend only along each side of the tank lining 28 thus leaving an open space at each corner of the tank lining. This open space is purposely left to allow for the installation and tightening of the turnbuckles 56 after the tank lining has been installed.

The opening may be closed by a deformable rubber plug 76 which may be snapped into place after the turnbuckles have been adjusted. This construction eliminates the necessity of leaving the back of the cabinet open for fastening the tank lining to the casing.

The door 26 for closing the provision compartment is made up of an outer panel 80 and an inner panel or lining 82 and the relation of these parts is more clearly shown in Figs. 7 and 8. The outer panel 80 has a return flange 84 extending completely around the back side of the panel.

This return flange 84 is in turn bent out along each side to form a flange 86 the function of which corresponds to the function of the flange 46 of the refrigerator casing. The door lining 82 has an outturned flange 88 corresponding in function to the flange 52 of the tank lining.

The two door panels are held together by means of turnbuckles 90 in much the same manner as the tank lining 28 is held to the casing 20. For this purpose, I have provided the metal strips 92 at each corner of the inner panel 82 and the gusset plates 94 at each corner of the outer panel. The strips 92 are bent double in the center to form the lugs 96 and are welded onto the flange 88. The gusset plate 94 is bent double to form the lug 98 and is welded to the return flange 84 of the outer panel between the return flange 84 and the outside of the panel. I have provided the flanges 93 on the edge of each gusset plate which are adapted to fit over the flanges 86 of the outer panel. The flanges 93 thus automatically locate the correct position for the gusset plate to be welded to the return flange 84.

The lugs 96 and 98 have holes 100 punched in them which are engaged by the turnbuckles 90. As in the connection between the tank lining and the cabinet, the inner and outer panels of the door are separated by separating strips 102 which engage the flanges 86 on the outer panel of the flanges 88 on the inner panel. The two panels may be drawn together against the opposite sides of the separating strips 102 by tightening the turnbuckles 90, and the open spaces at each corner of the door may be closed by deformable rubber plugs similar to the plugs 76 used in the cabinet. Of course, suitable insulating material will be packed into the outer panel 80 before the inner panel 82 and the separating strips 102 are installed.

In order to increase the capacity of the refrigerator without increasing its general dimensions, I have provided a door which is curved outwardly as shown at 104. This obviously allows the shelves 105 to be given a curved shape at their forward edge for increasing their effective area. In order to provide this curved door the inner panel 82 must be curved outwardly to be concentric with the outer panel 80. Thus, the inner panel 82 has a horizontal portion 106 at the top and bottom thereof which portion connects the curved portion of the panel with the flange 88 which is maintained in a vertical plane in order to be in alignment with the flange 86 of the outer panel. It should be noted that the flat portion 106 at the bottom of the panel 82 forms a convenient shelf which may be used while rearranging the contents of the provision compartment.

The return flange 84 of the outer panel may carry a channel member 108 completely around the door for the purpose of holding a flexible gasket 110. The channel 108 may be welded to the return flange 84 and the gasket 110 may be snapped into the channel 108. This gasket forms a seal between the door and the refrigerator casing.

With the above details of construction in mind it will be apparent that the refrigerator embodying my invention may be easily and cheaply assembled. The casing and tank lining may be made up each as a unit at no more expense than is now required for those parts of the refrigerator and may then be assembled by merely engaging the thermal separating strips and the turnbuckles with the lugs provided on the cas-

ing and tank lining and then tightening the turnbuckles. I have thus eliminated the work necessary to install a frame within the casing and the work necessary to fasten the casing and tank lining to the frame. The construction of the door is likewise simplified by eliminating the necessity of a separate frame.

I wish to point out that while the tank lining is supported directly from the outer casing it is still insulated therefrom. The separating strips acting as a thermal break between the two members. The only metallic contact between the casing and the tank lining is through the four turnbuckles and since the connection between the turnbuckles and the lugs on the casing is a line contact there will be very little area for heat leakage into the tank lining. The same insulating properties are present in the door construction which I have shown.

While I have described my invention with some detail I do not intend to be limited to the particular embodiment described but reserve the right to make such changes in equivalent structure as will fall within the purview of the attached claims.

I claim:

1. A casing defining a door opening, a lining in spaced relation to said casing, an inturned flange on said casing around said door opening, an outturned flange on said lining around said door opening, lugs having strips fastened to each corner of said flange on said casing, lugs having strips fastened to each corner of said flange on

said lining, turnbuckles engaging the lugs on said casing and said lining for drawing them together, insulating strips engaging the flanges on said casing and said lining along each side of said door opening and flexible insulating plugs adapted to be snapped into engagement with the flange on said casing and the flange on said lining at the corners thereof said turnbuckles being accessible for manipulation only through the openings closed by said flexible plugs.

2. A refrigerator door construction comprising an outer panel having a return flange, an inner panel having a flange around its edge turned towards said outer panel, a flange along each side of the return flange on said outer panel, a gusset plate fastened to each corner of said return flange on said outer panel, said gusset plate having a portion bent up to form a lug, another lug having strips fastened along each corner of the flange on said inner panel, rigid insulating strips adapted to engage the flange on said inner panel and the flange along each side of said return flange on said outer panel, adjustable fastening means engaging the lugs on said outer panel and the lugs on said inner panel adapted to draw said panels into engagement with said insulating strips and flexible insulating plugs removably fastened between the flange on said inner panel and the flanges on the return flange on said outer panel at the corners thereof, said fastening means being accessible when said flexible plugs are removed.

LEONARD H. DARBYSHIRE.
